US00D880683S

(12) **United States Design Patent** (10) **Patent No.:** **US D880,683 S**
(45) **Date of Patent:** **** Apr. 7, 2020**

(54) **CEILING FAN BLADE**

(71) Applicant: **Hunter Fan Company**, Memphis, TN (US)

(72) Inventors: **Bobby Neal Norwood**, Oakland, TN (US); **Christine Marie Holmes Bradley**, Memphis, TN (US); **Charles William Botkin**, Cordova, TN (US)

(73) Assignee: **Hunter Fan Company**, Memphis, TN (US)

(**) Term: **15 Years**

(21) Appl. No.: **29/656,002**

(22) Filed: **Jul. 10, 2018**

(51) LOC (12) Cl. **23-03**

(52) U.S. Cl. **D23/413**

(58) **Field of Classification Search**

USPC D23/370, 377, 379, 385, 411-414;

(57) **CLAIM**

The ornamental design for a ceiling fan blade, as shown and described.

DESCRIPTION

FIG. 1 is a top perspective view of a ceiling fan blade showing our new design;

FIG. 2 is a bottom perspective view thereof;

FIG. 3 is a top view thereof;

FIG. 4 is a bottom view thereof;

FIG. 5 is a rear view thereof, looking at a root of the ceiling fan blade;

FIG. 6 is a front view thereof, looking at a tip of the ceiling fan blade;

FIG. 7 is a left side view thereof;

FIG. 8 is a right side view thereof;

FIG. 9 is an enlarged view of the tip of the ceiling fan blade of FIG. 8; and,

FIG. 10 is an enlarged view of the root of the ceiling fan blade of FIG. 8.

Portions of the ceiling fan blade shown in broken lines form no part of the claimed design.

1 Claim, 7 Drawing Sheets
